CLAIM

The ornamental design for finger-held training device for instruction of snowboard maneuvering, as shown.

DESCRIPTION

FIG. 1 is a front perspective view showing a finger-held training device for instruction of snowboard maneuvering showing my new design;

FIG. 2 is a top plan view thereof; and

FIG. 3 is a side elevational view thereof;

FIG. 4 is a perspective view showing the assembled article;

FIG. 5 is a bottom view thereof.

FIG. 1.

FIG. 2.

FIG. 3.

FIG. 4.

FIG. 5.
